ATTACHMENT PLUG CAP

Nathan Chirclestein, Chicago, Ill.

Application March 1, 1938, Serial No. 193,242

5 Claims. (Cl. 173—361)

The invention herein disclosed relates to separable electrical connectors in the nature of attachment plug caps.

Special objects of the invention are to provide 6 a cord clamp for devices of this nature, which can be readily fully opened to receive the cord and which will automatically center itself in gripping engagement with the cord.

Other objects are to simplify and improve the 10 structure generally of attachment plug caps.

Further objects and novel features of construction, combinations and relations of parts by 15 which the objects of the invention are attained are set forth hereinafter and will be apparent from the following specification in conjunction with the accompanying illustration.

The drawing which may be considered as forming 20 part of the following specification illustrates practical and at present preferred embodiments of the invention. The structure however may be modified and changed within the scope of the invention as will be apparent from the following description and the broad scope of the claims defining the invention.

25 Fig. 1 is a broken top plan view of an attachment plug cap embodying the invention and shown with the cord clamp in opened relation to receive the cord.

Fig. 2 is a generally similar view showing the 30 clamp closed on the cord and the latter appearing in section.

Fig. 3 is a side view of the cap.

Fig. 4 is a bottom plan view showing the open 35 unobstructed character of the cord passage when the clamp is fully opened.

Fig. 5 is a side elevation with parts broken and in section as on line 5—5 of Fig. 2.

Fig. 6 is a broken detail illustrating the pivotal mounting for one of the clamp members.

40 Figs. 7, 8 and 9 are broken sectional details of modifications.

In the several views, the body of the plug cap is designated 10, and is shown as carrying attachment plug prongs 11, projecting from one 45 face of the same. These prongs are shown as secured simply by ordinary elongated tubular eyelets or hollow rivets 12, engaged over the bases 13, of the contact blades at one end and headed over at the opposite end into an annular 50 groove 14, at the opposite side of the plug body.

To avoid any possibility of the short circuiting of these blade securing eyelets, an annular disc 15, of insulating material is shown seated in groove 14, over the upper ends of the eyelets.

55 The body 10 which may be of resilient live

rubber is reinforced in the present disclosure by a plate 16, shown as secured over the upper end or top of the cap by elongated tubular rivets or eyelets 17, extending entirely through the body.

In addition to serving as a reinforcement for 5 the body, this plate serves as a mounting and support for the cord clamp.

The cord clamp comprises two duplicate clamping members 18, in the nature of levers, each having an angled base 19, at one end pivotally secured on the plate 16, as by a shouldered rivet 20, and having at the opposite free end a longitudinal slot 21, receiving the shank of a headed screw 22, threaded into the other companion clamp lever at 23, at a point inside or 15 toward the center from the pivot stud of that lever.

With the screws loosened up as in Fig. 1, the clamp levers will open up far enough to fully expose the cord passage 24, through the center 20 plug, enabling easy threading of the cord 25, into the plug. The tightening of either screw will have a closing and at the same time a centering effect on the two clamp levers, so that either screw may be started first and the final 25 tightening accomplished by turning both screws to substantially equal tension. In the first portion of the tightening movement, the screw being turned will have the effect of first drawing in the free end of the lever which it engages. 30 Then as that lever begins to take hold of the cord, the pull of the screw will have the effect of swinging inward the other lever which carries the screw seat for that screw. As the levers approach a more nearly closed relation, the pull 35 comes more nearly over the center of the lever pivots 20, as in Fig. 2, so that then the screws act almost as pulling directly against said pivot mounts. Under all these conditions of adjustment, the two levers will continue their substantially parallel relationship, substantially 40 equally centered with respect to the cord passage and gripping the cord substantially equally at opposite sides. In the final relationship, the cord is held properly centered at the end of the 45 plug cap, substantially as indicated in Fig. 5.

The clamp mounting plate 16, may have the edge of the same flanged inwardly as indicated at 26, Fig. 7, or 27, Fig. 8, to stiffen it and to provide a rounded outer shoulder 28. This edge 50 reinforcement enables a relatively light gage plate to be used for supporting the cord clamp and which does not add objectionably to the weight of the cap. If desired, the end of the body may be formed with a narrow annular 55

groove 29, to receive the edge flange of the clamp plate or the edge flange may be left somewhat sharpened as in Fig. 8, so that it will bite somewhat into the end surface when the body is formed of resilient material.

When the body is made of resilient material, the annular insulating washer 15, overlying the ends of the blade fastening eyelets serves the further purpose of insuring against short circuiting in the event that excess pressure is applied to the plug, such as might deform the body sufficiently to force the ends of the prong rivets into engagement with the clamp mounting plate. This mounting plate actually is simply a washer, having at the center an opening 30, somewhat larger than the cord passage in the body. The reinforcement gained by flanging the end of this washer as in Figs. 7 and 8, permits the washer to be made of light thin stock. The groove 14 into which the fastening eyelets extend may be quite narrow, that is, simply the width of the eyelet heads and quite shallow as the flanging of these eyelets takes up but small space. The insulating washer 15, while probably not essential, is considered desirable as providing a definite layer of insulation between the ends of the contact fastenings and the supporting plate. By locating the clamp pivots 20, for the two levers diametrically opposite and at opposite sides of the cord passage, the levers will be maintained in parallelism in the various positions of adjustment. This also enables the pivotally mounted end portion 31 of one lever to act as a positive stop for the slotted free end portion 32 of the other lever, thus to prevent the levers from ever moving closed past the center of the cord passage. By providing the seats 23 for the screws 22, in the pivoted end portions 31, of the levers and the slots 21, in the free ends of the levers, the screws maintain their approximate parallelism as they are tightened as will be apparent from Figs. 1 and 2.

As shown in Fig. 9, the end plate 16 may be increased to substantially the full diameter of the plug body and have an edge flange 33, seating over a shouldered portion 34, at the very edge of the plug. The coaction of the flange with this shouldered portion automatically centers the plate over the end of the plug and to an extent confines the plug so that it can not be distorted under unusual pressure. This provides a desirable plug construction, which in some instances, may be used without the clamp structure.

55 What is claimed is:

1. In an attachment plug cap, a plug body having a cord passage therethrough, a supporting plate at one end of said body, clamp levers having angled bases, means pivotally mounting the angled bases of said levers on the outer face of said supporting plate at opposite sides of said cord passage and in position with the free end of one lever opposite the pivoted angled base portion of the other lever and screws connecting said opposed free and said pivotally mounted end portions of the clamp levers, said screws being set inwardly toward the cord passage from the pivotal mounts of said levers.

2. An attachment plug cap having a central

cord passage, contacts at one end of said body, said body having a narrow annular groove in the opposite end of the same, fastenings extending from said contacts at one end through to said groove in the opposite end of the body, an annular insulating washer seated in said groove over the ends of said contact fastenings, a plate secured on the end of the body over said insulating washer, opposed cord clamp levers, means pivoting the ends of said levers on said plate at opposite sides of the cord passage with the free end of one lever adjacent the pivotally mounted end of the other lever and screws connecting the free ends of the levers with said pivotally mounted ends of the levers, said screws being disposed inward of the pivotal mountings toward the cord passage.

3. An attachment plug cap, comprising a resilient plug body having a narrow annular groove in one end, an end plate engaged over said end of the plug body and having an inwardly angled edge flange entered in said narrow annular groove, means securing said plate in flat abutting engagement over the end of said resilient plug body, said plate and plug body having passages for a cord, opposed cord clamping levers having angled ends engaged with said end plate at opposite sides of the cord passage therethrough, means pivotally securing said angled ends of said levers on said end plate and screws adjustably securing opposite end portions of said levers together.

4. An attachment plug cap comprising a resilient plug body having a cord passage therethrough and provided with a narrow annular groove in one end of the same adjacent the rim portion of the plug body, an annular end plate engaged over said end of the plug body, having a central cord passage and having a peripheral angularly projecting flange entered in said annular groove in the end of the plug body, opposed substantially parallel cord clamp levers, means pivotally mounting one end of each of said clamp levers over the outer face of said annular end plate at opposite sides of the cord passage and with the pivoted end of one lever opposite the free end of the other lever and screws adjustably securing the opposed end portions of said levers together.

5. An attachment plug cap, comprising a resilient plug body having a cord passage therethrough, a thin flat annular end plate secured over one end of said plug body and having a central cord passage in line with the cord passage in the plug body, opposed substantially parallel cord clamp levers, means pivotally mounting one end of each of said clamp levers over the outer face of said annular end plate at opposite sides of the cord passage and with the pivoted end of one lever opposite the free end of the other lever, one end of each lever having a screw seat and the opposing end of the other lever having a slot in line with the screw seat in the first mentioned lever and screws extending through said slots into engagement with said screw seats for drawing the free ends of the levers toward the pivoted ends of the levers in substantially parallel cord clamping relationship.

NATHAN CHIRELSTEIN.
